FLUID PRESSURE SWITCH

John V. Oliveau, Mineola, N. Y., assignor to The Aerotec Corporation, Greenwich, Conn., a corporation of Connecticut

Application April 19, 1949, Serial No. 88,351

10 Claims. (Cl. 200—81.5)

1

My invention relates to a fluid pressure control device and more particularly to a device of this type which is explosionproof and which may be readily adjustable without the necessity for opening it.

This invention is applicable to many different types of pressure control, such as differential pressures, subatmospheric pressures, etc.

In my present invention I provide a case to enclose the various elements, and more particularly the electric control switch and pressure actuated elements for operating same.

The pressure actuated elements are contained in a cylindrical shell closed at its ends and slideable axially in the case and having externally threaded end portions projecting a slight distance beyond the wall of the case. Threaded on these projecting ends are adjusting nuts preferably of annular shape, there being one nut for each projecting end, so that by loosening one and tightening the other the shell may be adjusted longitudinally and locked in adjusted position. The shell is held from rotational movement.

Mounted in the shell are one or more pressure controlled expandible elements, the expansion and contraction of which actuate an arm of the switch mounted in the case. Preferably the switch is actuated upon by a small ball carried by an expandible element in a suitable mounting means and bearing directly on the switch arm.

The case is not leakproof but has a slight clearance of, for example, one to a few thousandths of an inch, through which gases may pass under pressure. If an explosive mixture should be formed within the case and become ignited by a spark from the switch, the pressure developed will expel the products of explosion through the very fine passages provided so that they will escape gradually until the pressure is relieved and, through this gradual passage be cooled to normal temperature, or temperature of the case and, therefore, be unable to ignite any explosive mixture about the control mechanism or ignite or set fire to any combustible materials.

The various features of the invention are illustrated by way of example in the accompanying drawings in which

Fig. 1 is a view in elevation of an explosion-proof control mechanism embodying a preferred form of the invention;

Fig. 2 is a plan section of the mechanism taken on line 2—2 of Fig. 1;

Fig. 3 is a detail section on a somewhat larger scale taken on line 3—3 of Fig. 2;

Fig. 4 is a plan view of the control mechanism shown in Fig. 1;

2

Fig. 5 is a vertical section taken on the line 5—5 of Fig. 4;

Figs. 6, 7 and 8 are diagrammatic illustrations of modified forms of the control apparatus.

5 Referring more particularly to the accompanying drawings, the moving elements of the mechanism are enclosed in a case 10 having suitable lugs 11 secured to a mounting member and having an electric switch 12 mounted on a supporting base 13 on the inner surface of the case wall, as shown in Figs. 2 and 3.

The switch 12 is actuated by a lever pivoted at 13' on a bracket of the switch 12 and having an actuating arm 14 extending sidewise into a cylindrical shell 15 extending vertically through the opposite upper and lower walls 16 and 17 of the case and having an opening 18 through which the arm 14 passes.

15 The shell 15 is provided with a longitudinal slot 19, as shown in Figs. 2 and 3, into which projects the studs of a pair of screws 20 mounted in the vertical wall of the case and covered by a plate 21. The engagement of the studs of the screws 20 in the slot 19 permits the shell 15 to move longitudinally or axially in the case but prevents its rotational movement.

20 The ends of the shell 15 projecting through the walls 16 and 17 are externally threaded as at 22 and 23 and on these externally threaded portions are screwed adjusting nuts 24 and 25.

25 It will be apparent that by loosening one of these nuts and tightening the other the shell may be adjusted longitudinally without opening the case.

30 The ends of the shell are closed by plugs 26 on which are mounted one or more expandible elements, two such elements 27 and 28, in opposed aligned position, being shown by way of illustration in Figs. 1 and 5. Communication to the interior of these expandible elements is obtained by 35 passages through the plugs 26, ending in connecting projections 27' and 28'. The free ends of the expandible elements are connected by a connecting bridge piece 29, the position of which is dependent upon relative pressures in the expandible elements 27 and 28.

35 Movements by the bridge piece 29 are transmitted to the switch arm 14 by means of a bearing ball 30 contained in a recess in the yoke 29 which is closed partly about the ball to retain it in position.

40 It will be apparent, therefore, that the position of the switch 12 will depend upon the position of the yoke 29 and ball 30 governed by the relative 45 pressures or differences in pressures in the expandible elements 27 and 28. The differences in

pressure required to operate the switch arm 14 or to move it to a predetermined position may be adjusted by shifting the shell 15 longitudinally in one direction or the other by a suitable adjustment of the positioning nuts 24 and 25. And it is obvious that this adjustment may be made from the outside of the case and without opening or disturbing any of the parts. In order to prevent excessive movement of the expansible elements such as might result in their rupture, the projections or nipples are extended inwardly within the expansible elements as at 31 and 32.

In using a control device of the above type where combustible materials or gases are involved, there is always the possibility of an explosive mixture being formed within the case and about the control switch, as a spark may be formed by the opening of the switch elements and an explosion may arise within the case generating a high pressure.

In the present invention these explosive gases are permitted to escape through narrow passages in which they are rapidly chilled to the temperature of the case before escaping and, therefore, reduced much below the ignition temperature and thus rendered safe. These passages may be as small as $\frac{1}{1000}$ of an inch, or may amount to a few thousandths of an inch. These passages may be formed for example between the outer wall of the shell 15 and the inner surface of the case 30 closing the shell as, for example, at the points indicated at 33, 34, 35 and 36, and also between other fittings on the case such, for example, as between the surfaces of an outlet fixture 37 for electric wiring and the edges of an opening 40 in which it is mounted. Escape passages may also be formed in spaces as at 41, 42, between a cover plate 43 and adjacent parts of the case.

In the embodiment shown in Figs. 1 to 5 the switch is controlled by the difference in pressure between two different pressure sources as, for example, in a flow inductor comprising a calibrated orifice.

Other embodiments are illustrated in Figs. 6, 7 and 8. In Fig. 6 there is illustrated a switch which is altitude compensated, having a pressure bellows 27 which is opposed by an altitude bellows 28. The latter is evacuated and is provided with a spring 44. The atmospheric pressure acting on bellows 27 is balanced by the atmospheric pressure on bellows 28 so that the switch is actuated by the absolute pressure, the differences in atmospheric pressure at various altitudes being compensated. The bellows 28 is supported on an adjustable supporting stem 45.

In the embodiment shown in Fig. 7 the expansible element may be replaced by a spring 46 mounted on a supporting plate 47 supported by an adjusting screw 48 so that the expansible element 27 will operate solely against the spring 46. In this case the apparatus would be used as a straight gauge pressure switch.

A switch of the above type may be connected by means of a capillary tube and a temperature sensing bulb filled with a low boiling point liquid in which case the switch may be used as a temperature actuated switch. The sensing tube could be placed at a position remote from the switch.

In the embodiment shown in Fig. 8 a single bellows 27 is employed together with a spring 49 contained within the bellows. The bellows or expansible element 27 may then be evacuated so that it will expand when the pressure of the surrounding atmosphere decreases as, for example, with increase in altitude so that the switch will

operate when a predetermined altitude is reached. It may also be supported by an adjusting screw 50.

Through the above invention I have, therefore, provided an explosion-proof pressure actuated switch, the point of actuation of which may be adjusted readily from the exterior of an enclosing casing and without removing or opening any of the parts.

Having described my invention, what I claim is:

1. Fluid pressure control device which comprises a case, a cylindrical shell extending through said case and projecting through opposite walls thereof, said shell being movable axially but retained from rotation in said case, the projecting portions of said shell being externally threaded, the ends of said shell being closed, positioning nuts one threaded on each projecting portion of said shell to abut the wall of said case, an expansible element in said shell and an electric switch in said case outside of said shell and having an operating arm engaging said expansible element.

2. The control device of claim 1 in which said shell has a small clearance with the walls of said case to permit the escape of gases under pressure.

3. The control device of claim 1 in which said case is provided with escape passages of small clearance to permit the escape of gases under pressure.

4. The control device of claim 1 in which a bearing ball is mounted on said expansible element to bear against the arm of said switch.

5. The control device of claim 1 having a pin and groove connection between said shell and said case to prevent rotation of said shell in said case.

6. Fluid pressure control device which comprises a case, a cylindrical shell extending through said case and projecting through opposite walls thereof, said shell being movable axially but retained from rotation in said case, the projecting portions of said shell being externally threaded, the ends of said shell being closed, positioning nuts one threaded on each projecting portion of said shell to abut the wall of said case, a pair of opposed expansible elements in said shell, a connecting bridge piece between the opposed free ends of said expansible elements and an electric switch in said case outside of said shell having an operating arm engaged by said connecting bridge piece.

7. The control device of claim 6 in which a bearing ball is mounted on said bridge piece to bear against the arm of said switch.

8. The control device of claim 7 in which a spring is provided to bear against one of said expansible elements.

9. The control device of claim 1 in which a spring is mounted to oppose said expansible element.

10. The control device of claim 1 in which a spring is mounted within and acting to expand said expansible element.

JOHN V. OLIVEAU.
